Attorney.

UNITED STATES PATENT OFFICE.

EDWARD D. ROCKWELL, OF BRISTOL, CONNECTICUT, ASSIGNOR TO THE
BRISTOL BELL COMPANY, OF SAME PLACE.

BICYCLE-BELL.

SPECIFICATION forming part of Letters Patent No. 621,759, dated March 21, 1899.

Application filed December 27, 1898. Serial No. 700,314. (No model.)

To all whom it may concern:

Be it known that I, EDWARD D. ROCKWELL, a citizen of the United States, and a resident of Bristol, in the county of Hartford and State 5 of Connecticut, have invented certain new and useful Improvements in Bicycle-Bells, of which the following is a full, clear, and exact description, whereby any one skilled in the art can make and use the same.

10 My invention relates to the class of devices used on a bicycle or like vehicle for sounding a warning or alarm; and the object of my invention is to provide a bicycle-bell with means whereby the thumb-lever or push-button used for operating the mechanism may have its position with respect to the clamp changed as may be desired to accommodate the bell to varying conditions of use in attachment to different parts.

15 To this end my invention consists in the device as a whole, in the combination of parts, and in the details and their combination, as hereinafter described, and more particularly pointed out in the claims.

20 Referring to the drawings, Figure 1 is a view in side elevation of a bicycle-bell embodying my invention. Fig. 2 is a detail top or plan view of the same with the gong removed. Fig. 3 is a detail view, in central 25 vertical section, through the base-piece and clamp with the striking mechanism and gong removed. Fig. 4 is a detail view showing in elevation the gong-post, the thimble, and one section of the clamp separated. Fig. 5 shows detail end views of these parts.

30 In the accompanying drawings the letter *a* denotes the clamp as a whole; *b*, the bell-base; *c*, the thumb-lever, and *d* the gong of a bicycle-bell. The clamp, as to its clamping features, 35 may be of any desired construction, a form in common use at the present time having been selected for the purpose of illustrating herein my improvement. This clamp has a clamp-base *e*, through which is a hole *e'*. In 40 the preferred form of the invention this hole has tapering walls, as shown in the drawings, being smaller at that end next to the bell-base than at the opposite end.

45 A thimble *f* is formed, as to its outer surface, to fit the hole *e'* at or near its inner end, and by "inner end" I mean that end next

to the bell-base, this fit being such as to allow free turning movement of the thimble within the hole in the clamp-base. The end wall *f'* of this thimble has an opening *f''* of such 55 shape in cross-section as to prevent a post *g* from turning therein, the opening in the form shown being oblong. The thimble when secured in place forms what may be termed a "hub" for the bell-base. The post *g* extends 60 through the bell-base and is secured in the opening *f''*, preferably as by means of riveting. The opening in the bell-base is made to conform to the shape of the end of the post, and that part of the post extending 65 through the bell-base and clamp-base is reduced, as shown in the drawings. This means of securing the post in position is the ordinary form now employed in bells of this class.

A set-screw *h* extends through the wall of 70 the clamp-base *e*, its end seating against the outer surface of the thimble. The end of this set-screw is preferably tapered, such form having special advantages when used in connection with a thimble having tapering or 75 flaring sides in that the clamp-base and bell-base are drawn tightly together as the set-screw is turned to place.

The thimble and hole through the bell-base are shown and described herein as tapered, 80 such forms having special advantages in that the parts are thus secured against separation; but it is to be understood that such forms are not necessarily essential to the invention 85 herein.

Bell-striking mechanism of any desired form may be used in connection with the device, mechanism employing a thumb-lever, push-button, or like operating means, however, having special advantages when used in 90 connection with my improvement.

Although a set-screw operated by a screw-driver is shown herein as a ready means for adjusting the bell-base at the same time and with the same tool as is employed to secure 95 the clamp, it is to be understood that such means for clamping the clamp-base to the thimble are not essential to the invention.

I claim as my invention—

1. In combination in a bicycle-bell, a clamp, 100 a bell-base, a hub rigidly secured to one of said parts and adapted to be located in an

- opening in the opposite part, means for clamping the hub against movement in the opening, bell-striking mechanism with means for operating the same, and a gong supported in operative relation to the bell-striking mechanism.
2. In combination in a bicycle-bell, a clamp having a clamp-base with an opening therein, a bell-base having a hub rigidly secured thereto and adapted to be located in said opening, means for clamping the hub against movement in the opening, bell-striking mechanism with means for operating the same, and a gong supported in operative relation to the bell-striking mechanism.
3. In combination in a bicycle-bell, a clamp, a bell-base, a tapered hub rigidly secured to one of said parts and adapted to be located in a tapered opening in the opposite part, means for clamping the hub against movement in the opening, bell-striking mechanism with means for operating the same, and a gong supported in operative relation to the bell-striking mechanism.
4. In combination in a bicycle-bell, a clamp having a clamp-base with a tapered opening therein, a bell-base having a hub rigidly secured thereto and adapted to fit within said opening, means for clamping the hub against movement therein, bell-striking mechanism with means for operating the same, and a gong supported in operative relation to the bell-striking mechanism.
5. In combination in a bicycle-bell, a clamp, a bell-base, a tapered hub on one of said parts adapted to be located in a tapered opening in the opposite part, a set-screw seating against the hub, bell-striking mechanism with means for operating the same, and a gong supported in operative relation to the bell-striking mechanism.
6. In combination in a bicycle-bell, a clamp having an opening, a bell-base, a thimble rigidly secured against rotation to the bell-base and fitting the opening in the clamp, means for clamping the thimble against movement in said opening, bell-striking mechanism with means for operating the same, and a gong supported in operative relation to the bell-striking mechanism.
7. In combination in a bicycle-bell, a clamp having a tapered opening, a bell-base, a tapered thimble rigidly secured against rotation to the bell-base and fitting the opening in the clamp, means for clamping the thimble against movement in said opening, bell-striking mechanism with means for operating the same, and a gong supported in operative relation to the bell-striking mechanism.
8. In a bicycle-bell, in combination, a clamp having an opening, a bell-base, a thimble fitting the opening in the clamp, a gong-post extending through the bell-base and thimble and rigidly securing them together against relative rotation, means for clamping the thimble against movement in said opening, bell-striking mechanism with means for operating the same, and a gong supported in operative relation to the bell-striking mechanism.
9. In combination in a bicycle-bell, a clamp, a bell-base, a hub on one of said parts adapted to be located in an opening in the opposite part, a clamping device seating against said hub and securing it against movement in the opening, bell-striking mechanism with means for operating the same, and a gong supported in operative relation to the bell-striking mechanism.
10. In combination in a bicycle-bell, a clamp having a clamp-base with an opening therein, a bell-base having a hub adapted to be located in said opening, a clamp device seating against said hub and holding it against movement in the opening, bell-striking mechanism with means for operating the same, and a gong supported in operative relation to the bell-striking mechanism.
11. In combination in a bicycle-bell, a clamp, a bell-base, a tapered hub on one of said parts adapted to be located in an opening in the opposite part, a set-screw having a tapered surface engaging the tapered surface on the hub, bell-striking mechanism with means for operating the same, and a gong supported in operative relation to the bell-striking mechanism.

EDWARD D. ROCKWELL.
